UNITED STATES PATENT OFFICE.

ANDREW SCHAEFER, OF LOUISVILLE, KENTUCKY.

MACHINE FOR MAKING BROOMS FOR STREET-SWEEPING MACHINES.

SPECIFICATION forming part of Letters Patent No. 729,676, dated June 2, 1903.

Application filed October 27, 1902. Serial No. 128,863. (No model.)

To all whom it may concern:

Be it known that I, ANDREW SCHAEFER, a citizen of the United States, residing at Louisville, in the county of Jefferson and State of Kentucky, have invented certain new and useful Improvements in Machines for Making Brooms for Street-Sweeping Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in a machine for making brushes for pick-up street-sweeping machines; and the object of my invention is to so construct such a machine as to make its operation more rapid and economical and the details of construction more convenient.

In the drawings, Figure 1 is a right-hand end elevation. Fig. 2 is a rear side elevation. Fig. 3 is a front side elevation. Fig. 4 is a top plan view showing the bed of the machine partly broken away. Fig. 5 is a sectional detail view showing the relative position of the parts of the broom at the beginning of the operation of the machine, and Fig. 6 is a similar view of a broom completed by the machine.

A represents the supporting-legs of the machine.

A' represents the bed of the machine, from each end of which projects an arm A², on which slides a drill-carriage C, bearing drills C², arranged at suitable distances throughout its length from one end of the carriage to the other, the boring end of the drills directed inwardly toward the bed of the machine and the outward end of the drills carrying operating-pulleys c c c. From the right-hand end of the carriage, as shown in Fig. 2, arms C' descend vertically, arranged to support a main driving-pulley for the drills, (designated by D.) Supported by arms descending from the other end of the carriage is an idler D' for the drill-belt d, which passes around the main driving-pulley D, then around the idler D', then alternately over the pulleys c c on the ends of the drills and corresponding idlers c' c', arranged below the drill-carriage.

Along the length of the bed A and parallel with its longitudinal axis I arrange metal bars B, having flanges B' at suitable distances apart to hold the side braces of the broom in position. These bars are fastened to the bed of the machine by bolts b', passing through the flanges and through transverse adjusting-slots a' in the bed of the machine, whereby the distance between the bars B can be adjusted to suit the size of the broom.

b b represent transverse grooves in the bars B to allow the passage of the drills, and a a represent openings in bottom of the machine-bed to let drill-dust and shavings drop through.

E represents the vertical pressure-bar frame, and E' the pressure-bar which works between vertical guiding-standards A³; V-shaped on their inner opposite sides and connected at the top by a cross-piece A⁴. On the lower bar of the frame E, below the bottom of the bed, is a flange e³, projecting inwardly, adapted to engage dogs F', attached to the legs A of the machine by coiled springs f.

F represents the dog trip-bar, and f' the connection between the trip-bar F and the dog-bar f².

F² represents lever-handle to disengage dogs.

G represents the main drive-pulley for pressure-frame.

G' is a small pinion on shaft of main pulley.

G² is a large gear on the cam-shaft.

G³ and G⁴ G⁴ represent cams.

g g are standards projecting upward from the bottom bar of the pressure-bar frame E, and g' represents rollers on top of the standards g to engage the cams G⁴.

The reference-letters e e indicate the longitudinal half-U-shaped wooden side braces of the broom; e', the longitudinal wooden center brace of the broom; e², a flat iron bar laid along the middle of the bed A' to keep the bottoms of the broom sides apart, and H the bristles or straw forming the sweeping portion of the broom.

The operation of my machine may be described as follows: When a broom is to be made, the half-U-shaped side braces are placed longitudinally on the bed A' of the machine parallel and opposite, the concave sides facing each other, their backs resting

against the bars B, and their bottoms kept apart by the longitudinal bar e^2 . The straw H is laid across the side braces e, as shown in Fig. 5. The pressure-bar frame E is counterbalanced by weights W, attached by pulleys P to ceiling or wall, as shown in Fig. 3, the power being applied by the belt around the pulley G. The cam-shaft G³ is thrown over by the lever G⁵ till the cams engage the rollers g' on top of the standards g, erected on the bottom bar of the pressure-bar frame E, whereupon the pressure-bar frame is forced down, bringing the pressure-bar E' down with it till the dogs F' engage the projecting flange e² on the bottom bar of the frame E and hold the frame fast. As the pressure-bar E' descends it engages the center piece e' of the broom throughout its length, forcing it down and carrying the straw down before it, as indicated in Fig. 5. At this point it would be preferable to use the lever G⁵ to disengage the cams from the rollers g'. As soon as the center piece e' is forced into position over the straw and between the side braces of the broom the main drive-pulley D, carrying the drill-belt d, is put in motion, causing the drills C to revolve. The drill-carriage is moved inwardly by the screw-shaft marked I (shown partly broken off) by either power or hand till the drills cut through the side braces and center brace of the broom, when the carriage is drawn back to its original position, and the bolts to hold the sides and center brace of the broom together are put through the holes made by the drills and fastened by screw-taps, as shown in Fig. 6, the dust or shavings from the drills falling through the apertures a in the bottom of the bed A'. The broom complete is then removed, the lever F² is thrown back, disengaging the dogs from the flange e³, and the counterbalanced frame E rises to its original position, with the pressure-bar E' pressing against the top piece a⁴, joining the guide-standards A².

This machine runs by power and can be adjusted to any-sized brush or to put any desired number of bolts in a brush. The drills mounted on the drill-carriage drill all the holes for bolts through the broom at the same time and the drills and idlers can be adjusted to use as many or few as desired.

Having thus described my invention, what I claim, and now desire to secure by Letters Patent of the United States, is—

1. In a machine for making brooms for street-sweeping machines, the combination with a support having means for holding in proper relative positions the side portions of a broom-head, of a plurality of drills for boring holes through said side portions of the broom-head, a reciprocatory pressure device for forcing the broom-straw into place in the broom-head, and means for operating said drills and pressure device.

2. In a machine for making brooms for street-sweeping machines, the combination

with a bed, and bars extending longitudinally thereof and adapted to secure the sides of the broom-head in proper relative position between them, said bars having openings, of a reciprocatory carriage provided with a series of drills arranged opposite said openings, means for reciprocating said carriage and rotating said drills, a reciprocatory pressure-bar for forcing the broom-straw into position in the broom-head, and means for reciprocating said pressure-bar.

3. In a machine for making brooms for street-sweeping machines, the combination with a support having means for holding in proper relative positions the side portions of a broom-head, of a reciprocatory pressure device for forcing the broom-straw into position between said portions of the head, means for raising said device and means for holding the same in lowered position.

4. In a machine for making brooms for street-sweeping machines, the combination with a frame having means for holding in proper relative positions the side portions of a broom-head, of a counterbalanced pressure device for forcing the broom-straw into position between said side portions of the head, and a dog and a projection to engage each other, one of which is carried by said reciprocatory device, for holding the same in lowered position.

5. In a machine for making brooms for street-sweeping machines, the combination with a frame having means for holding in proper relative positions the side portions of a broom-head, of a counterbalanced pressure device for forcing the broom-straw into position between said portions, a pair of spring-pressed dogs pivoted to said frame, projections from said pressure device to engage said dogs at one end of said limit of travel of said device, means connecting said dogs with each other and means for disengaging said dogs from said projections.

6. In a machine for making brooms for street-sweeping machines, the combination with a support having means for holding in proper relative positions the side portions of a broom-head, of a shaft provided with cams, a frame having a means for forcing the broom-straw into position between said portions of the head, projections from said frame to be engaged by said cams, and means for rotating said shaft.

7. In a machine for making brooms for street-sweeping machines, the combination with a frame having means for holding in proper relative positions the side portions of the broom-head, of a counterbalanced frame provided with a pressure-bar for forcing the broom-straw into position between said side portions, means for holding said frame at one extremity of its movement against the action of its counterbalancing means, and means for releasing said frame from said holding means.

8. In a machine for making brooms for

- street-sweeping machines, the combination with a frame having means for holding in proper relative positions the side portions of a broom-head, of a counterbalanced reciprocating frame having a pressure-bar for forcing the broom-straw into position between said side portions, means for holding said frame at one extremity of its movement against the action of its counterbalancing means, and means for releasing said frame from said holding means, a shaft, means for operating said shaft and means operated by said shaft for moving said reciprocating frame in one direction.
- 15 9. In a machine for making brooms for street-sweeping machines, the combination with a frame having means for holding in proper relative positions the side portions of a broom-head, of a counterbalanced reciprocating frame having a pressure-bar for forcing the straw into position between said side portions, means for holding said frame at one extremity of its movement against the action of its counterbalancing means, a longitudinally-adjustable and axially-movable shaft, means for shifting the same longitudinally, a cam thereon, a projection from said counterbalanced frame to be engaged by said cam, and means for rotating said shaft.
- 20 10. In a machine for making brooms for street-sweeping machines, the combination with a support having means for holding in proper relative positions the side portions of a broom-head, of a counterbalanced pressure device for forcing the broom-straw into posi-

tion between said side portions, means for holding said device against the action of its counterbalancing means, and means for drilling holes in the side portions of the broom-head while said pressure device is holding the straw in place between the same.

11. In a machine for making brooms for street-sweeping machines, the combination with a suitably-supported bed bearing on its surface two parallel bars with an interval between them, of a quadrangular, vertically-arranged counterbalanced frame, having a top bar adapted to fit in the interval between the bed-bars, working between guide-standards projecting upward from the bed, side bars outside the guide-standards a bottom bar with an inwardly-projecting flange and standards having rollers at the top projecting upward near each end, a shaft journaled in the legs of the machine-bed bearing cams adapted to engage the rollers on the projecting standards of the bottom bar of the frame E and force the frame downward, dogs attached to the legs of the machine-bed adapted to engage the flange on the bottom bar, means for actuating the cam-shaft and means for disengaging the cams and dogs, substantially as described and for the purposes specified.

In testimony whereof I affix my signature in presence of two witnesses.

ANDREW SCHAEFER.
